UNITED STATES PATENT OFFICE.

JOSEPH LYONS SEARFOSS, OF PROVIDENCE, RHODE ISLAND.

DREDGING DEVICE.

SPECIFICATION forming part of Letters Patent No. 774,280, dated November 8, 1904.

Application filed February 19, 1904. Serial No. 194,328. (No model.)

To all whom it may concern:

Be it known that I, JOSEPH LYONS SEARFOSS, a resident of the city of Providence, in the county of Providence and State of Rhode Island, have invented certain new and useful Improvements in Dredging Devices; and I do hereby declare that the following is a full, clear, and exact description thereof, reference being had to the accompanying drawings, and to the numerals of reference marked thereon, which form a part of this specification.

This invention relates to improvements in dredging-machines, and has for its object the construction of simple, practical, and effective means for successfully operating that style of dredging-bucket commonly known as the "clam-shell" bucket and "orange-peel" or other pole-operated bucket. The methods heretofore employed have been unsuccessful in operating this class of bucket for dredging in rough water or on a hard bottom, as poles have to be used to guide the bucket while being raised and lowered, and when the bottom is at all hard the bucket has to be held down rigidly by said poles in order to make the jaws bite into the substance on which it rests. While dredging in rough water the waves raise and lower the dredging-scow, causing the bucket to be lifted clear of the bottom and then dropped down again with great force, often breaking its poles or raising the boom, and its work is very unsatisfactory and in many cases impossible. When the bucket is dropped to the bottom of the river, its jaws are open to the extreme, nearly at right angles to the line of the poles. As it lies on the bottom in this position it is held down by said poles, and when the bucket rests on a gravel or hard sandy bottom and the power is applied to close the jaws its edges must necessarily be forced down into the material or something above must give way and allow the poles to be forced upward. The latter result is usually the case, rendering the work of this class of bucket under these conditions very ineffective.

The object of this invention is to obviate all of the above difficulties by regulating the tension or pressure on the bucket through the poles. This is done by grips or binding-yokes which are operated through a flexible connec-

tion from a revolving drum and controlled by a friction-brake. This flexible connection also retains the boom in place and gives the necessary pressure to the bucket on the bottom of the river while operating.

55

The invention consists of other novel features and parts and combinations of the same, as will be fully described hereinafter and then pointed out in the appended claims.

A practical embodiment of the invention is represented in the accompanying drawings, forming a part of this specification, in which similar characters of reference indicate corresponding parts in all the views.

Figure 1 is an elevation illustrating the position and relation of the different parts. Fig. 2 is an enlarged top plan view of the grip-yoke and the mechanism for operating the same. Fig. 3 is a side elevation illustrating the mechanism shown in Fig. 2. Fig. 4 is a detail of a band-brake such as may be used in controlling the tension of the flexible connection on said grip-yokes and the boom. Fig. 5 shows a modification illustrating a cam for operating the grip-yoke which may be used in place of the crank-motion shown in the other figures and operated by the same flexible connection. Fig. 6 illustrates the position taken by the jaws of the bucket when open.

80

In the drawings, 1 denotes a portion of the dredging-scow in section, on which all of the operating mechanism is carried. At 2 is the boom, which is pivotally held on the deck of the scow at 3 to swing laterally in the usual way and carry the bucket to either side when it is required to discharge its contents. On the outer end of this boom is a platform 4, on which is supported and secured the mechanism for gripping and holding the poles of the bucket. At 5 is the bucket of the well-known clam-shell type, which is hung from and operated through the poles 6, which poles are set one on either side into the sockets 7 in the usual way. These poles project upward through the locking mechanism on the platform 4 above and are necessarily made very long, so that they will reach to the bottom of the river. Secured to this platform 4 is the fixed jaw 8 of the grip-yoke, (see Fig. 2,) 100

which is bolted to said platform. At 9 is the reciprocating jaw on the opposite side of said poles, which is arranged to slide laterally in the guides 10 10, which guides are secured to 5 said platform on either side thereof. Guide pins 11 11 are secured to said reciprocating jaw and extend through corresponding holes in the fixed jaw, one on either end of the same. Cranks 12 12 are mounted on the shaft 13 and 10 are connected to the lug 14 of the reciprocating jaw 9 by the connections 15 15. At 16 is the outwardly-extending arm on which is adjustably secured the counterbalance-weight 17. The grooved pulley 18 is mounted on 15 and fixed to the shaft 13, which shaft is supported at either end on bearings 29 29. The wire rope 19 has a turn around this pulley, with one end fixed thereto, and extends down to the front end of the scow, over the idler-pulley 20, and back to the drum 21, around 20 which drum this rope may have one or more turns. This drum is driven from the gear 22 through the pinion 23 and is controlled in its speed and tension by the action of the brake 24, which brake in turn is controlled by the 25 operator. The gear 22 is mounted on the main shaft 25, on which shaft is also mounted the drum 26, by which drum the opening and closing of the bucket is controlled through 30 the connection 27.

The operation of the machine is further described, as follows: When this type of bucket is dropped to the bottom of the river, it is opened, as illustrated in Fig. 6, in the usual 35 way by mechanism not shown, but well understood by those skilled in their use. In closing this bucket again a considerable power has to be exerted through the wire-rope connection 27, the strain of which naturally has 40 a tendency to raise the bucket. Then, again, as hereinbefore described, in attempting to close the jaws of this bucket when it is resting on hard bottom, the natural tendency being to raise instead of embedding itself into 45 the hard material, the strain is again materially increased. Under the above conditions it will be seen that a great strain must be withstood by the poles and by the boom 2, that supports the whole from its end.

5c I have found that in actual operation it is impractical under many conditions to drop the bucket onto the bottom of the river and permanently lock it there while it is being closed without some means for regulating or 55 controlling the tension on it. I have therefore constructed a drum 21, which is mounted on the shaft 28, which shaft is continuously driven from the main shaft through the gears 22 and 23 while the bucket is being operated. 60 The drum 21 may be operated from said shaft 28 through a clutch or brake 24 or by any other suitable method for controlling at will the tension of the rope which is wound around it. When the bucket is not working and it is 65 desired to release the same, the clutch or fric-

tion is thrown out by the lever 24^a and the drum is released, the weight 17 on the end of the lever 16 drops and pulls open the jaws of the grip-yoke automatically, and the poles are free to move up and down. When the bucket 70 is dropped onto the bottom of the river and before the power is applied to close it, the operator throws in the friction-clutch and starts the drum 21 to rotating, the wire rope 19 is tightened up, the counterbalance-weight 75 17 is raised, the pulley 18 revolves, and the cranks 12 12 descend, closing the sliding jaw 9 of the grip-yoke onto the poles 6 6. Then as the power is applied to close the jaws of the bucket 5 the strain on the wire rope 19 is increased in proportion to counterbalance the upward strain of the bucket. Thus the poles are locked in position and the end of the boom is supported and held down against the great upward strain. The tension on both the poles 80 and the boom may be increased or diminished at will by regulating the friction on the drum 20. The bucket may be made to cut in as much or as little as desired, and its operation is nicely controlled. When operating in rough 85 water, the bucket is dropped to the bottom and the rising and dropping of the scow is compensated for in a great measure by releasing and tightening up on the rope 19, which supports the end of the boom.

95 My invention is not restricted to the precise construction and arrangements of parts herein shown and described nor to the various details thereof, as the same may be modified or re-arranged in various particulars without departing from the spirit and scope of my invention, one practical embodiment of which has been herein illustrated and described without attempting to show all of the various forms and modifications in which my invention might be 100 embodied.

105 Having thus described my invention, what I claim as new, and desire to secure by Letters Patent, is--

110 1. In a dredging-machine, a boom supported at one end, a bucket supported by poles from the opposite end of said boom, means whereby the outer end of said boom is held from rising and means for automatically locking the poles.

115 2. In a dredging-machine, a boom having one end pivotally supported from said machine, a bucket suspended by poles from the outer end of said boom, means for locking said poles in the desired position and flexible means adapted to be set up and hold the outer end of the boom from rising.

120 3. In a dredging-machine, a boom having one end pivotally supported, a bucket suspended by poles from the opposite end of said boom, and means for holding the outer end of said boom from rising and at the same time automatically locking the said bucket-poles in the desired position.

125 4. In a dredging-machine, a boom having 130

one end pivotally supported from the machine, a bucket suspended by poles from the opposite end of said boom, flexible means for holding the outer end of said boom from rising 5 and means for automatically locking said bucket-poles in the desired position.

5. In a dredging-machine, a boom having one end pivotally supported from the machine, a bucket suspended by poles from the opposite 10 end of said boom, flexible means for holding the outer end of said boom from rising, means for automatically locking said bucket-poles in the desired position and means whereby the tension on said boom through said flexible means may be increased or diminished at 15 will.

6. In a dredging-machine, a boom having one end pivotally supported from the machine, a bucket suspended by poles from the opposite 20 site end of said boom, a revolute drum on said dredging-machine, a flexible connection controlled by said drum and leading therefrom to said boom to support said boom from rising and means for locking said bucket-poles. 25

7. In a dredging-machine, a boom having

one end pivotally supported from the machine, a bucket suspended by poles from the opposite end of said boom, a revolute drum on said dredging-machine, a flexible connection from said drum to said boom to support said 30 boom from rising, and means for automatically locking said bucket-poles by the tension of said flexible connection.

8. In a dredging-machine, a boom having one end pivotally supported from the machine, 35 a bucket suspended by poles from the opposite end of said boom, a revolute drum on said dredging-machine, a flexible connection from said drum to said boom to support said boom from rising, jaws for gripping and 40 binding the bucket-poles and means whereby said jaws are actuated to engage and hold said poles when said flexible connection is set taut.

In testimony whereof I have hereunto set my hand this 17th day of February, A. D. 45 1904.

JOSEPH LYONS SEARFOSS.
In presence of—

CHARLES E. HICKEY,
GEORGE CURTIS MORGAN.
